(No Model.)

C. D. HARRIS.

AUTOMATIC FEED REGULATOR FOR GAS BURNERS.

No. 393,008.

Patented Nov. 20, 1888.

UNITED STATES PATENT OFFICE.

CHARLES D. HARRIS, OF CICERO, INDIANA.

AUTOMATIC FEED-REGULATOR FOR GAS-BURNERS.

SPECIFICATION forming part of Letters Patent No. 393,008, dated November 20, 1888.

Application filed May 24, 1888. Serial No. 274,961. (No model.)

To all whom it may concern:

Be it known that I, CHARLES D. HARRIS, a citizen of the United States, residing at Cicero, in the county of Hamilton and State of Indiana, have invented a new and useful Improvement 5 in Automatic Feed-Valves, of which the following is a specification.

My invention relates to an improvement in automatic feed-regulating valves for gas-burners; and it consists in the peculiar construction and combination of devices, that will be more fully set forth hereinafter, and particularly pointed out in the claims.

The object of my invention is to provide a 15 feed-regulator for a gas-burner which is adapted to be operated automatically by changes of temperature, so as to preserve an even temperature in the room or apartment in which the gas-heater is located.

20 In the drawings, Figure 1 is partly a side elevation and partly a vertical sectional view of a feed-regulator embodying my improvements. Fig. 2 is a vertical sectional view of the same taken on the line xx of Fig. 1. Fig. 3 is a top 25 plan view thereof.

A represents the base plate, which is provided on its upper side with a boss, B. In the upper end of the said boss is a circular recess or depression, C, and communicating with the 30 center of said recess or depression is an opening, D, which communicates with the gas-pipe E.

F represents an escape-opening, which is also made in the base-plate and communicates 35 with the recess C near the opening D, and in the said opening F is secured one end of a pipe, G, which supplies gas to the heating-burner, (not shown,) said burner being arranged in a suitable grate, fire-box, stove, or other receptacle.

40 From the foregoing it will be understood that the gas must pass from the opening D through the recess C and into the opening F before it can reach the burner.

H represents a metallic diaphragm, which is arranged on the upper side of the boss so as to cover the recess C, and is secured firmly on the boss by a circular plate, I, which is screwed to the boss and has a central circular 50 opening of suitable size to expose the major portion of the diaphragm.

K represents a curved spring-arm, which has

one end bearing on the center of the diaphragm. A screw, L, passes downward through the arm K, near the outer end thereof, and enters the 55 plate A, and another screw, M, passes upward through said plate and bears against the under side of the outer end of the arm at a suitable distance beyond the screw L. By turning said screws L and M the spring-arm may 60 be caused to bear upon its diaphragm at any desired pressure, so as to keep the same normally closed over the openings D F, as will be readily understood.

To the ends of the plate A are secured standards or posts N, which extend upward therefrom. A beam, O, is provided with vertical openings near its ends, through which the posts extend, and said beam is arranged at a suitable distance above the plate A, and is provided with transverse diagonal grooves P in its under side, and has a vertical opening, R, which is arranged above the diaphragm. Bolt rods S extend upward from the plate A through the beam O, and have clamping-nuts 75 T at their upper ends, which bear upon the said beam.

U represents a beam which connects the upper ends of the post N, and is provided in its upper side with transverse oblique grooves V, 80 which extend in the opposite direction from the grooves P.

1, 3, 5, and 7 represent a series of yoke-levers, which are provided at gradually-varying distances from one end with trunnions X, 85 which are wedge-shaped in transverse section and have feather-edges at their lower sides, which bear in recesses Y in the upper side of the beam and communicate with the grooves. In the ends of the said yoke-levers are open 90 slots Z. 2, 4, and 6 represent a series of similar yoke-levers, which are arranged in the grooves P of the beam O, and have similar feather-edge trunnions arranged at bearing distances from their ends and bearing in recesses in the under side of said beam.

B' represents a rod, which is made of zinc, brass, or some other metal which is adapted to contract and expand to a maximum extent under varying temperatures. The lower end of 100 said rod is secured firmly in beam O, and the upper end of said rod is threaded and passed through a central opening in a saddle, C'. Said saddle is triangular in cross-section and

of a length somewhat in excess of the width of the yoke-levers, and the lower feather-edge of said saddle is inserted in a transverse recess in the upper side of the yoke-lever, near 5 one end of said yoke. The upper end of said rod B' is arranged in the open slot at the end of the lever, and provided with a clamping-nut, D', that bears on the saddle. The opposite end of the yoke 1 is connected to one end 10 of yoke-lever 2 by a rod, E', and a pair of similar saddles, which engage the upper and lower sides of said yoke-levers, respectively. A rod, E', and similar saddles connect the levers 2 and 3. A rod, E', and similar saddles connect 15 the levers 3 and 4. A rod, E', and similar saddles connect the levers 4 and 5. A rod, E', and similar saddles connect the levers 5 and 6. A rod, E', and similar saddles connect the levers 6 and 7, and to one end of the lever 7 is 20 similarly connected a similar rod, F', which passes downward through the opening R and has its lower end connected to the free end of the spring-arm K. By this arrangement of the 25 thermostatic rods and the yoke-levers said thermostatic rods are caused to contract and expand throughout their combined lengths, and thus cause the rod F', which is attached to the spring-arm, to move to a maximum extent in a vertical direction.

30 The operation of my invention is as follows: When the heat in the room or apartment exceeds the required degree, the thermostatic rods expand, so as to permit the arm K to exert greater pressure on the diaphragm, and thereby cause the same to partly cut off the 35 supply of gas to the burner by closing more tightly on the openings D and F. When the temperature becomes lowered, the thermostatic rods contract, and thereby cause the arm K 40 to move upward from the diaphragm, so as to cause the latter to permit an increased quantity of gas to be supplied to the burner, as will be readily understood. The bolt-rods S contract and expand with the thermostatic rods, 45 and thereby move the beam O very slightly on the posts N, and consequently aid the operation of the thermostatic rods. Said posts N are preferably made of some material which will contract and expand only to the minimum 50 extent.

In order to prevent the supply of gas from being entirely cut off from the burner when the diaphragm closes on the openings D F, I provide a needle-pointed valve, H', which is 55 adapted to control a small channel, H'', between the openings D F, and to cause a small quantity of gas to be fed to the burner continuously, independently of that fed thereto by the diaphragm. The quantity of gas fed by the

said needle-pointed valve may be controlled by adjusting the said valve, as will be readily understood.

Having thus described my invention, I claim—

1. The combination of the plate A, having 65 openings D F, the channel C, connecting said openings, through which the gas passes, the diaphragm secured on said plate and adapted to regulate the size of the gas-channel, the arm bearing on the diaphragm to normally 70 close the same on the gas-channel, and the thermostatic rod connected to the said arm to operate the latter, substantially as described.

2. The combination, in a thermostatic gas- 75 feed regulator, of the diaphragm, the spring-arm K, having one end bearing thereon, the screws to regulate the pressure of said spring-arm on the said diaphragm, and the thermostatic rod connected to said arm, substantially 80 as described.

3. The combination of the beams or supports, the series of yoke-levers having the fulcrums at varying distances from their ends and bearing on the supports, the thermostatic 85 rod B', connecting one end of one of the said levers to a rigid support, the intermediate thermostatic rods connecting the ends of the levers together in continuous series, the rod 90 E', attached to one of said levers at its free end, and the gas-regulating valve connected to said rod, substantially as described.

4. The combination of the base-plate having the gas-channel and the diaphragm to regulate the size thereof, the posts N, extending 95 from the base-plate, the beam U, connecting the upper ends of said posts, the beam O, adapted to move on the post, the bolt-rods S, connecting said beam to the base-plate, the yoke-levers having their fulcrums on the 100 beams U O, and the thermostatic rods connecting the said levers in series, one of said rods being attached to the diaphragm, substantially as described.

5. The gas-regulating valve having the channel through which the gas passes, the diaphragm to regulate the size of said channel, the thermostat to automatically operate said diaphragm, and the valve, substantially as set forth, to feed gas independently of the gas-channel, substantially as described. 105

In testimony that I claim the foregoing as my own I have hereunto affixed my signature in presence of two witnesses.

CHARLES D. HARRIS.
